CHAIN PRESS

Richard F. Kreiter, Houston, Tex.

Application June 15, 1939, Serial No. 279,267

9 Claims. (Cl. 59—7)

This invention relates to a chain press.

An object of the invention is to provide a machine for removing the pins connecting the links of a sprocket chain as well as for replacing said pins.

The links of sprocket chains as commonly manufactured are connected by pins, the connecting pins having a pressed fit in some of the links and a loose fit through the other links to give the required flexibility to the chain and in use it is sometimes necessary to remove these connecting pins for making repairs such as substituting new links for broken ones or for lengthening or shortening the chain. The invention herein described has been specially designed for removing and replacing the chain pins when it becomes necessary to substitute new links for old ones or to lengthen or shorten the chain.

It is another object of the invention to provide a portable machine that will be instantly available when required.

It is another object of the invention to provide a chain press of the character described that may be manually operated and which is so constructed that the manual power applied to the operating handle will be multiplied when applied to the actual work of forcing the chain pins out of or into the link bearings.

While the press has been primarily designed for removing and replacing sprocket chain pins it is adaptable for use for analogous purposes.

With the above and other objects in view the invention has particular relation to certain novel features of construction, operation and arrangement of parts, an example of which is given in this specification and illustrated in the accompanying drawings, wherein:

Figure 1 shows a plan view of the press.

Figure 2 shows a side elevation, partly in section.

Figure 3 shows a cross-sectional view taken on the line 3—3 of Figure 2.

Figure 4 shows a fragmentary, plan view of the bed showing the sprocket plate as being applied thereto.

Figure 5 shows a cross-sectional view taken on the line 5—5 of Figure 2.

Figure 6 shows an enlarged, fragmentary, longitudinal sectional view taken on the line 6—6 of Figure 1 showing the parts in position to begin the operation.

Figure 7 shows a view similar to Figure 6, but showing the parts at the end of a working cycle.

Figure 8 shows an enlarged, cross-sectional view taken on the line 8—8 of Figure 1 showing

the parts in an intermediate position during the completion of a stroke, and

Figure 9 shows a similar view showing the parts at the end of a working stroke.

Referring now more particularly to the drawings wherein like numerals of reference designate the same parts in each of the figures, the numeral 1 designates the bed of the press which, at one end is reduced in width forming the extension 1a which is formed with a transverse bore 2 into which there is pressed a tubular bushing 3 to receive the transverse rod 4 whose ends project each way beyond the bed. Rotatably mounted on the projecting ends of the rod 4 are the eccentric spindles 5, 5 which fit snugly within the front bearings 6, 6 of the connecting rods 7, 7. The eccentric spindles, or cams, 5 are formed integrally with the central hood 8 forming a handle block and having the sockets 9, 9 to receive the handles 10. The bearings 6 may be held against detachment from the cam shaped spindles by means of suitable cotter keys 11, 11.

It is obvious that as the handles 10 are oscillated the connecting rods 7 will be correspondingly oscillated.

At its forward end the top of the bed 1 is countersunk thus forming the opposing shoulders 12, 12 curved on a common circle and provided with the arcuate grooves 13, 13. A sprocket plate 14 is provided. The opposing ends of this sprocket plate have the arcuate tongues 15, 15. In application the sprocket plate is seated in the countersunk portion of the bed transversely of said bed, as shown in Figure 1 and then given a quarter turn so that the tongues 15 will seat in the grooves 13 as shown in Figure 2 in which position the sprocket plate may be maintained by a suitable pin fitted through the openings 16, 17, which will align when the sprocket plate is properly positioned on the bed as shown in Figure 2. The sprocket plate 14 has the required number of rows of sprockets as 18 which are received by the links of the sprocket chain as 19, as shown in Figure 3, when the chain is positioned on the press.

The sprocket plate, as is obvious, can readily be removed and another substituted for it having the required number of sprockets to receive the particular size of type of chain to be operated on.

50 The opposite, or rear, end of the bed, is also reduced in width forming the rear extension 1b whose upper margin has a wide groove 20. As will be noted from an inspection of Figure 2 the upper surface of the rear extension 1b is elevated above the upper surface of the forward portion of the

bed. The groove 20 forms a track to receive the rack bar 21 which is seated in and which moves along said groove. The upper face of the rack bar 21 has the rearwardly pitched ratchet teeth 22. The forward end of the rack bar 21 is formed with an upstanding head 23 having a plane forward face against which the plunger block 24 abuts. Said block has the forwardly extending push pins, or plungers, 25, 25. These plungers are of a diameter less than the diameter of the chain pins to be operated on. These chain pins will vary in diameter in accordance with the type of sprocket chain and consequently the plunger block 24 and its pins 25 must be changed to provide push pins of the required diameter; hence the plunger block 24 is made separate from the head 23.

A ratchet block 26 is fitted over the rack bar 21 and embraces the rearward extension 1b and is movable therealong. This ratchet block has, in its under face, ratchet teeth 27 pitched the reverse of the pitch of the teeth 22 and engageable with said last mentioned teeth. The ratchet block has the end trunnions 28, 29 and fitted over these trunnions are the eccentric sleeves, or cams, 29, 29.

Fastened to the outer ends of the sleeves 29, 29 are the upstanding arms 30, 30 which are connected to move in unison by the cross-rod 31 and one of said arms 30 is extended upwardly forming a hand lever 32. A strong pull spring 33 is connected at its rear end to one of the arms 30 and at its forward end is attached to a rod 7 and is under sufficient tension to normally tend to pull the arms 30 forwardly. The rear ends of the connecting rods 7 are formed with the circular bearings 34, 34 which closely surround the eccentric sleeves 29.

Mounted in a suitable transverse bearing in the rear extension 1b there is a transverse cam shaft 35 and fixed to and upstanding from this shaft there is an operating handle 36. Fixed on this shaft and aligned underneath the respective connecting rods 7 are the cams 37 on which the connecting rods rest. Upon manipulation of the handle 36 forwardly the cams 37 will be turned to lift the rear ends of the connecting rods 7 and to thus elevate the ratchet block 26 so that its teeth will clear the teeth 22. Behind the ratchet block and secured to opposite sides of the rear extension 1b, are the upstanding standards 38, 38 whose upper ends have aligned bearings to receive the ends of the transverse rod 39 and fixed on this rod there is a dog 40 which may be engaged with the teeth 22, as shown in Figures 2 and 3, to prevent the rearward movement of the rack bar 21. Upon elevation of the ratchet block 26, as hereinabove explained, and upon disengagement of the dog 40 from the teeth 22 the rack bar 21, the anchor block 24 and the push pins, or plungers, 25 may be retracted or moved the required distance rearwardly.

In operation the chain to be operated on may be located on the sprocket plate 15 with the sprockets 18 projected upwardly between the links of the chain as shown in Figure 3 and the handle 36 moved rearwardly so that the ratchet block 26 will be in its lower position with its teeth engaged with the teeth 22 and the dog 40 swung into its forward position, as shown in Figure 2, to engage the teeth 22. With the hand lever 32 in its forward position, as shown in Figure 2, and also as shown in Figure 7, the high sides of the eccentric sleeves 29 will be rearwardly as shown in Figure 7 and the high sides of the ec-

centric spindles 5 will be upwardly as shown in Figure 3, with the handles 10 in upright position as also shown in Figure 3. In this position it will usually require too much power to start the chain pins as in some cases it requires a very high pressure to start the pins to move. Therefore, in starting the work the hand lever 32 should be moved rearwardly to its rear position as shown in Figure 6. This, as is obvious, will turn the eccentric sleeves 29 until their high sides are forwardly thus permitting a slight forward movement of the connecting rods 7, 7 so that the handles 10 can be swung forwardly thus giving a better leverage as indicated in Figure 8. It is to be noted that the chain should be adjusted to the exact right height so that the push pins, or plunger, 25 will exactly align with the pins connecting the chain links. In order to accomplish this adjustment, a series of set screws as 41 are provided in the sprocket plate 15 between the sprocket teeth. These set screws 41 may be adjusted to the exact required height and the chain when positioned in place will be supported on them.

It is preferable to employ a guide as 42 for guiding the push pins, or plungers, 25. This guide is shaped substantially like a chain link and has bearings to receive the push pins 25 and which align with the chain pins when said guide 42 is located on the sprocket plate as clearly shown in Figure 1. The guide 42, when positioned in place, as shown in Figure 1, will abut the opposing side link of the chain. Upon manipulation of the handles 10 in a downward direction the eccentric spindles, or sleeves, 5 will be turned in a direction indicated by the arrows in Figures 2 and 8 thus exerting a pull, through the connecting rod 7 on the ratchet block 26 which pull will be transmitted to the rack bar 21 and through it to the push pins, or plungers, 25 and these will operate against the chain pins as 19a forcing the same outwardly as is indicated in Figure 1. The handles 10 may then be swung upwardly rotating the eccentric spindles, or cams, 5 in a direction the reverse of that indicated by the arrows in Figures 2 and 8. The tension on the connecting rods 7 will thus be relieved and said connecting rods permitted to move rearwardly and the pull spring 33 will thereupon be permitted to pull the arms 30 forwardly thus partially rotating the eccentric sleeves 29 in the direction indicated by the arrow in Figure 6, the distance of said rotation being determined by the distance the handles 10 have been elevated. Thereupon the handles 10 may again be moved downwardly, as before, again moving the rack bar 21 and plungers 25 forwardly. When the pins 19a are once unseated, or started, and do not require so much power to move them, the range of handle stroke may be increased since less power is required and a greater leverage accordingly is permitted.

The operation is continued until the arms 30 approach the limit of their forward movement and the handles 10 are then swung upwardly to the limit of their forward movement as shown in Figure 2 thus permitting a final forward movement of the arms 30 which will cause the eccentric sleeves 29 to move correspondingly into position as shown in Figure 7 with their high sides rearwardly. The rearward movement of the connecting rods 7, 7 will cause a rearward movement of the ratchet block 26 but the dog 40 will hold the rack bar 21 against rearward movement thus holding the push pins, or plungers, 25 against the opposing ends of the chain pins 19a.

This rearward movement of the ratchet block 26 will cause its teeth to engage behind the next succeeding corresponding teeth of the rack bar 21, or in other words, will cause said ratchet block to take a new hold on the rack bar. The operation is then repeated as before gradually moving the rack bar 21 forwardly and gradually forcing the chain pins 19a outwardly. Attention is directed to the fact that upon oscillation of the handles 10 up and down as above explained, the rack bar 21, upon each oscillation will move forwardly only a portion of the distance between the teeth 22, the distance of each partial forward movement depending on the range of oscillation of the handles 10 and this range may be varied depending on the amount of power required to be applied. If the pins 19a are firmly seated and require great power to be moved the range of oscillation of the handles 10 will be less than after the pins have been started and require less power to accomplish their movement.

It is advisable in starting or unseating any chain pins 19a that short push pins 25 be first used to avoid danger of bending them as would likely happen if long push pins were used where a maximum power is required. When it becomes necessary to assemble the chain, that is, to force the chain links in place the guide 42 is placed over a sprocket 18 behind, and abutting, a side link of the chain and push pins are fitted loosely through the aligned bearings of all the links so as to maintain them in alignment and the chain pins are then forced, by the head 23, into place, by manipulation of the handles 10 in the manner hereinabove described, said chain pins gradually displacing the aligning push pins previously inserted through the link bearings.

The drawings and description are illustrative merely, while the broad principle of the invention will be defined by the appended claims.

What I claim is:

1. Apparatus of the character described comprising a support, a work holder associated therewith, power delivery means including an oscillatable cam, a connecting rod arranged to be reciprocated by the cam, a plunger adapted to operate against the work on the holder, means for actuating the plunger against the work, means connecting said rod to the actuating means and including a cam and means for actuating said last mentioned cam to permit movement of said rod, relative to said plunger-actuating means, in one direction but to prevent such relative movement in the other direction.

2. Apparatus of the character described comprising a support, a work holder associated therewith, power delivery means including an oscillatable cam, a rod having connection with, and adapted to be reciprocated by, the cam, a plunger arranged to be operated against the work on the holder, means for actuating the plunger against the work, means engageable with said actuating means and effective to advance the latter, and the plunger, upon movement of said advancing means in one direction, means connecting said rod to the advancing means and including a cam, means constantly tending to actuate said last mentioned cam to permit movement of the rod relative to the advancing means in one direction and to prevent such relative movement in the other direction, whereby to cause successive effective movements of the advancing means upon reciprocation of the rod.

3. Apparatus of the character described comprising a support, a work holder associated there-

with, power delivery means including a reciprocable connecting rod, a plunger adapted to operate against the work on the holder, means for actuating the plunger against the work, means connecting said rod to the actuating means and including a cam and means for actuating the cam to permit movement of said rod, relative to the plunger-actuating means in one direction but to prevent such relative movement in the other direction.

4. Apparatus of the character described comprising a support, a work holder associated therewith, power delivery means including a reciprocable connecting rod, a plunger arranged to be operated against the work on the holder, means for actuating the plunger against the work, means engageable with said actuating means and effective to advance the latter and the plunger, upon movement of said advancing means in one direction, means connecting said rod to the advancing means and including a cam, means constantly tending to actuate said cam to permit movement of the rod relative to the advancing means in one direction and to prevent such relative movement in the other direction whereby to cause successive effective movements of the advancing means upon reciprocation of the rod.

5. A chain press comprising a bed, a work holder therein shaped to receive an anchor, a sprocket chain, a reciprocable handle, a plunger adapted to operate against a chain pin to move the same into or out of the chain link bearings, cams arranged to be oscillated by the handle connecting rods having bearings on said cams whereby oscillation of the cams will reciprocate the rods, a rack bar operable against the plunger and having ratchet teeth, a ratchet block having teeth arranged to co-act with the teeth of said bar, cams oscillatable on the ratchet block, said rods having bearings on the ratchet block cams, means constantly tending to actuate said last mentioned cams to permit movement of the rods relative to the ratchet block in one direction and to prevent such relative movement in the other direction whereby to cause successive effective movements of the ratchet block and rack bar upon reciprocation of said rods.

6. Apparatus of the character described comprising a bed, a work holder thereon, a reciprocable power delivery means, a plunger adapted to operate against the work on the holder, means connecting the power delivery means to the plunger and including a member having a wedge-like action and means for actuating said member to permit movement of the power delivery means relative to the plunger in one direction but to prevent such relative movement in another direction.

7. Apparatus of the character described comprising a bed, a work holder thereon, reciprocable power delivery means, a plunger adapted to operate against the work on the holder, means connecting the power delivery means to the plunger and including a member having a wedge-like action whereby movement of the power delivery means relative to the plunger is permitted in one direction only.

8. In a chain press having a support, a work holder thereon, a slidable rack bar movable towards said work holder, a ratchet block having means arranged to co-act with the rack bar, a connecting rod, a cam oscillatable on the ratchet and connecting said rod to the block, means for reciprocating said rod, means tending to actuate the cams to permit movement of the rod rela-

tive to the ratchet block in one direction and to prevent such relative movement in the other direction whereby to cause successive effective movements of the ratchet block and rack bar upon reciprocation of said rod.

9. In a chain press, a bed having an arcuate recess, and a groove around the recess, a sprocket

plate having chain holding sprocket teeth thereon, said plate having arcuate ends corresponding to the shape of said recess, a tongue on the plate co-acting with the groove, means for aligning said plate on the bed.

5
